UNITED STATES PATENT OFFICE.

PHILIP MCHALE, OF NEW BEDFORD, MASSACHUSETTS.

DRAWING-ROLL FOR DRAWING AND EVENING ROLLS.

1,323,297.

Specification of Letters Patent.

Patented Dec. 2, 1919.

Application filed February 16, 1918. Serial No. 217,646.

To all whom it may concern:

Be it known that I, PHILIP MCHALE, a citizen of the United States, residing at New Bedford, in the county of Bristol and State 5 of Massachusetts, have invented new and useful Improvements in Drawing-Rolls for Drawing and Evening Rolls, of which the following is a specification.

This invention relates to improvements in 10 the construction of drawing rolls for drawing and evening machines, and more particularly to a novel construction of top drawing roll whereby the rolls are adapted to compensate for variations in the weight or 15 thickness of the sliver and to vary their drawing or evening action to secure an even and regulated speed of the material.

One object of the invention is to improve 20 the construction of the top drawing roller for machines of the character described whereby the said roller is adapted to have movement relative to the lower drawing roller to sustain as varying degrees throughout its length as the case may require, to 25 vary the speeding pressure according to the weight or thickness of the different portions of the sliver being acted upon.

Another object of the invention is to provide means for regulating the pressure of 30 the upper drawing roller on the lower drawing roller, and to thereby enable the machine to produce a sliver of any desired weight, whether heavy or light, and without changing the speed of the rollers or changing the 35 unfinished sliver or changing gear.

With the above and other objects in view 40 the invention consists in the construction, combination and arrangement of devices hereinafter described and claimed.

This invention is an improvement on the drawing roll for which Letters Patent of the United States No. 1,191,366 were granted to me on Feb. 24, 1914.

In the accompanying drawings:—

45 Figure 1 is a sectional elevation of a portion of a drawing and evening machine showing the application of my invention.

Fig. 2 is a rear elevation of the same, partly in section.

50 Fig. 3 is a detailed longitudinal sectional view of the upper drawing roll and associated parts.

Fig. 4 is a detailed vertical sectional view of the same on the plane indicated by the 55 line 4—4 of Fig. 3.

Fig. 5 is a similar view of the same on the plane indicated by the line 5—5 of Fig. 3.

Fig. 6 is a detailed perspective view of one of the bushings.

Fig. 7 is a similar view of one of the 60 springs.

The frame of a drawing and evening machine is indicated at 1, the lower fluted beading or drawing roll is indicated at 2 and the shaft 3 of said lower roll is mounted in 65 bearings 4, the said bearings having vertical slots 5 in their upper portions and which slots are open at their upper ends. Bearing blocks 6 are also shown, through which the shaft 3 extends, the said bearing blocks being arranged at a suitable distance from the 70 ends of the said rolls.

The upper fluted beading or drawing roll is indicated at 7 and in accordance with my 75 said invention comprises a non-circular shaft 8, fluted roll sections 9 and bushings 10 which are arranged in said roll sections and through which the shaft 8 extends, each of the said bushings being cylindrical in form and being provided with a central longitudinal slot 11 in which the shaft 8 fits, the 80 said slots being open at their upper sides so that said bushings are arranged for vertical movement with respect to the shaft. The shaft is here shown as rectangular in 85 cross section. The shaft passes through and is vertically movable in vertical slots 12 of bearing blocks 13, the said bearing blocks having recesses 14 in their lower sides and being fitted by means of said recesses on the 90 upper sides of the blocks 6. Regulating screws 15 pass through and engage in vertical threaded openings in the shaft 8. Said regulating screws bear at their lower ends on the bottoms of the slots 12, their upper 95 portions being free to rotate in unthreaded openings in the upper portion of the blocks 13, as shown in detail in Figs. 3 and 4. Spacing collars 16 are mounted on the shaft 8 between the series of roll sections 9 and the blocks 13. Sleeves 17 are fixed on the 100 ends of the shaft 8 by means of set screws 18 and have outer angular end portions 19 which engage and are vertically movable in the slots 5. The sleeves are also provided 105 with annular grooves 19 which are engaged by hooks 20, said hooks serving to suspend the usual weight 21 by means of which the upper roller is weighted and caused to press downwardly on the lower roll. The length 110

of the roll section 9 is such that each roll section 9 is adapted in connection with the lower roll 2 for drawing and evening two ends of cotton sliver.

5 A spring 22 is provided for each roll section 9. The said springs are here shown arcuate in form but may be of any suitable kind. Each spring 22 is arranged in the slots 11 of one of the bushings 10 and bears 10 between the bottoms of said slots and the lower sides of the shaft 8 so that each roll section is forced downwardly by its spring and said roll sections are afforded independent vertical movement with relation to the 15 drawing roll, whereby the rolls are adapted to accommodate themselves to variations in the weight or thickness of the cotton sliver. Each spring 22 has a pin 23 extending vertically from the center thereof. The said 20 pins operate in vertical openings in the shaft 8 and the lower ends of the said pins which are reduced as at 24 engage in central openings in the lower portions of the bushings as shown in detail in Figs. 3 and 5. The upper roll may also be adjusted vertically, as a 25 whole, by means of the screws 15. As the evening of the sliver is obtained by crimping the sliver between the upper and lower fluted rolls, to obtain a heavy sliver the upper roll is lowered by appropriately turning the screws 15 and thereby forcing the shaft 8 downwardly. This increases the 30 pressure on the spring 22 and hence causes said spring and the bushings 10 to force the roll sections 9 downwardly. This forces the sliver more deeply in the flute. When a lighter sliver is desired this is obtained by turning the screws 15 so that said screws raise the shaft 8 and thus diminish the 35 pressure on the springs 22 and correspondingly diminish the downward pressure of the roller sections 9, as will be understood. In 40

practice, the bushings are made of wood, chemically treated and do not require lubricating.

45

It will be noted that by means of my improved construction, hereinbefore fully described, the weight of the finished sliver can be changed from light to heavy or from heavy to light, as desired without changing 50 the speed of the rolls or changing the unfinished sliver or changing gears, which is a very great advantage as will be apparent to those skilled in the art to which my invention relates.

55

Having described the invention what is claimed is:—

1. In a machine of the class described, the combination with a shaft, roll sections loosely surrounding said shaft, and yieldably associated therewith, of standards, bearing blocks recessed at one end to fit on said standards, each block having a vertically disposed slot through which the shaft is passed for vertical adjustment, and an adjusting element threaded to the shaft and having one end bearing against the lower wall of said slot, whereby the shaft may be adjusted vertically to vary the tension of 60 said yieldable means.

65

2. In a machine of the class described, a shaft, roll sections loosely surrounding said shaft, a bushing in each section, said bushing being substantially U-shaped in cross section, a pin projecting from each bushing 70 through said shaft, a leaf spring fixed at its center between said pin and bushing and having its opposite ends yieldably supporting said shaft, and means for adjusting said shaft vertically to vary the tension of 75 said spring.

80

In testimony whereof I affix my signature.

PHILIP McHALE.
